(57) **CLAIM**

The ornamental design for a power source for a power operated screwdriver, as shown and described.

DESCRIPTION

FIG. 1 is a front view of a power source for a power operated screwdriver showing my new design;

FIG. 2 is a rear view thereof;

FIG. 3 is a side view thereof;

FIG. 4 is the opposite side view of FIG. 3 thereof;

FIG. 5 is a top view thereof;

FIG. 6 is a bottom view thereof; and,

FIG. 7 is a perspective view thereof.

The material appearing in dotted lines is environmental only and does not form part of the claimed design.
